(57) **CLAIM**

The ornamental design for a massage board, as shown and described.

DESCRIPTION

FIG. 1 is a top, perspective view of a massage board; FIG. 2 is a bottom, perspective view thereof; FIG. 3 is a left elevation view thereof; FIG. 4 is a right elevation view thereof; FIG. 5 is a back elevation view thereof; FIG. 6 is a front elevation view thereof; FIG. 7 is a top plan view thereof; FIG. 8 is a bottom plan view thereof; and, FIG. 9 is an in use view thereof.

The surface of FIGS. 1-9 are lightly lined for contour only. The broken lines in FIG. 9 showing the massage board in use illustrate the environment and form no part of the claimed design.
